UNITED STATES PATENT OFFICE.

LOUIS SIEVERT, OF FORT WAYNE, INDIANA.

DESIGN FOR A SPOON.

SPECIFICATION forming part of Design No. 35,359, dated December 3, 1901.

Application filed September 28, 1901. Serial No. 76,966. Term of patent 14 years.

To all whom it may concern:

Be it known that I, LOUIS SIEVERT, a citizen of the United States, residing at Fort Wayne, in the county of Allen and State of Indiana, have invented and produced a new and original Design for Spoons, of which the following is a specification, reference being had to the accompanying drawing, forming part thereof.

10 The figure of the drawing is a plan view of a spoon, showing my new design.

The leading or material feature of my design consists in the arrangement of the two shields 1 and 2 at the outer end of the handle of the spoon and the embellishment of said shields and the bowl 4 with wreaths 5,

6, and 7, respectively, within the centers of which are made portraits representing Abraham Lincoln, James A. Garfield, and William McKinley.

Having described my invention, what I claim as new, and desire to secure by Letters Patent, is—

20 The design for a spoon, as herein shown and described.

25 In testimony whereof I have signed my name to this specification in the presence of two subscribing witnesses.

LOUIS SIEVERT.
